UNITED STATES PATENT OFFICE.

GUSTAVE STICKLEY, OF SYRACUSE, NEW YORK.

DESIGN FOR A TABLE.

SPECIFICATION forming part of Design No. 35,045, dated September 3, 1901.

Application filed July 22, 1901. Serial No. 69,332. Term of patent 7 years.

To all whom it may concern:

Be it known that I, GUSTAVE STICKLEY, a citizen of the United States, residing at Syracuse, in the county of Onondaga, State of New York, have invented and produced a new and original Design for Tables, of which the following is a specification, reference being had to the accompanying drawing, in which I show the same in an isometrical view.

As shown in the drawing, the leading or material feature of my design comprises a table having a substantially circular top *a* and substantially rectangular legs *b*, the upper ends of which extend through the top *a*, as shown at *c*, and *d* represents cross-bars between opposite legs and passing through

them, as shown at *e*, the said cross-bars *d* intersecting each other centrally and having an angularly-headed bolt *g* uniting them, the whole forming a unique artistic table as an article of furniture.

Having thus described my invention, what I claim, and desire to secure by Letters Patent, is—

The design for a table substantially as herein described and shown.

In witness whereof I have hereunto set my hand this 9th day of July, 1901.

GUSTAVE STICKLEY.
